United States Patent Office.

JAMES WHITE, OF CLEVELAND, OHIO.

Design No. 3,505, dated May 18, 1869.

DESIGN FOR A TRADE-MARK.

The Schedule referred to in these Letters Patent and making part of the same.

To all whom it may concern:

Be it known that I, JAMES WHITE, of Cleveland, in the county of Cuyahoga, and State of Ohio, have invented certain new and useful Improvements in Designs for Grape-Box Labels; and I do hereby declare that the following is a full and complete description of the same, reference being had to the accompanying drawings, making part of this specification.

This invention relates to a design for a trade-mark, to be placed upon a fruit-box, in which grapes are packed, the same being especially intended for that particular variety of fruit.

The character of said design is as follows:

It is of a circular form, the outer border representing a grape-vine, A, within which are arranged, at regular and equal distances, grape-leaves, alternating with tendrils of variable coils.

The central portion of the design represents a circular sheet of paper, C, placed within the border, and upon the leaves referred to, so that a portion of them is covered and hidden under it.

On the upper half of this circular sheet of paper is displayed a bunch of grapes, D, hanging from a piece of vine, with a large leaf on either side, a portion of each leaf being hidden by the position of the fruit.

Immediately above the cluster of grapes is the name of the particular variety, which, in the drawing, is Catawba. The name of any other variety of this fruit may be inserted in place thereof.

On the lower half of the circular sheet is shown a little girl, seated upon the ground, bareheaded, with

her hat on one side of her, and on the other, a basket, books, and slate, with a few scattered grape-leaves near by. In her lap are seen some bunches of grapes, while she holds one in her left hand, from which she has plucked a grape, and appears about to eat it.

In the distance is seen a grapeviny, where persons are gathering the fruit, at the right hand of which is a dwelling, surrounded by trees, with a few poplars in the rear.

Beyond the vineyard and cottage is seen a line of hills, with some trees along the plains or base, which make up the background of the picture and landscape.

Immediately above the picture, and under the cluster of grapes at the left, is shown a figure 3, F, and at the right the letters "lbs," G, thereby indicating the number of pounds of fruit the box contains, which, however, may be more or less, as this label is intended for different-size boxes.

Between the figure 3 and letters lbs., is the word "from," underneath which will be printed, or written, the name of the person, company, or place, from which the fruit was sent, or put up.

What I claim as my improvement, and desire to secure by Letters Patent, is—

A design for a trade-mark, substantially as herein described, and for the purpose specified.

JAMES WHITE.
